UNITED STATES PATENT OFFICE.

LEANDER L. BARTLETT, OF MONTAGUE, MASSACHUSETTS.

PLANING-MACHINE.

SPECIFICATION forming part of Letters Patent No. 578,712, dated March 16, 1897.

Application filed October 21, 1896. Serial No. 609,521. (No model.)

To all whom it may concern:

Be it known that I, LEANDER L. BARTLETT, a citizen of the United States, residing at Montague, in the county of Franklin and 5 State of Massachusetts, have invented certain new and useful Improvements in Planing-Machines, of which the following is a specification, reference being had therein to the accompanying drawings.

10 My invention relates to an improved attachment for planing-machines for planing the taper on segments for fishing-rods.

The invention is illustrated in the accompanying drawings, in which—

15 Figure 1 is a plan of the machine with portion of bed broken away the better to show the device by which the taper is made. Fig. 2 is a side elevation of the same.

In the drawings, A is the main bed of the 20 machine, constructed with a side projection or table B, upon which rests the material to be operated upon.

25 C C C are feed-rolls held together by springs and rotated by means of the pulleys D D and the shafts c c, revolving in the journals d d d d.

E is an evening-cutter to size the stocks to an even thickness. This cutter is rotated by means of the pulley E' and shaft e', revolving 30 in journals e e.

F is a hollow cutter with the knives set at an angle of sixty degrees, so that six of the 35 segments form a complete circle. This cutter is rotated by means of the pulley f', revolving in the journals f f. These journals are a part of the carriage G, which is free to move vertically and is controlled by the cam H and weight W, which serves to keep the 40 carriage G in close contact with the cam H at the point G', where there is a pulley to relieve friction.

The cam H is intermittently rotated by means of the pulley H', which turns loosely on the cam-shaft l and is held in position by 45 means of the screw and washer l'. This pulley H' rotates continuously. h is a clutch on the pulley H', and h' is a corresponding clutch free to move laterally by means of a feather on the shaft l.

50 I is a bent lever hinged at I', and passing up through and above the table B terminates

in a rounded end, or with a friction-pulley, as shown at i.

J is a rod connecting the hinged lever I with the bent lever K, as shown at K' in Fig. 55 2. The bell-crank lever K is hinged at k and has a projecting arm k', which ends in a fork, engaging with the clutch h' in such a manner that when the rod J is moved in the direction of the arrow the clutch h' is thrown forward 60 and engages with the clutch h, and the cam H is caused to rotate. The lever K has also a projecting arm K², at the extremity of which is loosely hinged the rod R. This rod extends along toward the cam H and is of sufficient 65 length to be operated upon by the pin P, placed in one side of the cam H. At a point in the rod R is hinged a connecting-rod m, connecting with the arm M, which, by means of the arm N, operates the sliding bolt O, 70 75 which passes vertically through the stand supporting the lever K. These two arms M and N are securely fastened to the shaft N', so that they act simultaneously. The arm N works in a slot in the sliding bolt O, as shown in Fig. 2.

S and S' are spiral springs, the spring S serving to keep the clutches h and h' apart, and the spring S' serving as a counterbalance to the rod R. 80

The operation of my improved device is as follows: The piece to be planed is placed on the table B and passed under the cutter E, where it is planed to an even thickness, and thence passing between the feed-rolls C C it is gradually fed toward the cutter F. Just before it strikes the cutter F it passes over the end i of the bent lever I, forcing it downward and causing the rod J to move in the direction of the arrow, as shown in Fig. 2, and being connected with the bent lever K and its forked arm k' throws the clutch h' into gear with the clutch h, causing the cam H to begin a revolution in the direction of the arrow, as shown in Fig. 2. In the meantime the sliding bolt 95 O passes down and by the lever K, thus securing it safely until the cam H has made an entire revolution. The friction-roll G' of the carriage G, resting upon the outer surface of the cam H, is gradually raised by the revolving cam H, thus causing the piece operated upon to be planed on a gradual taper or in-

cline. The cam H, having made one complete revolution, brings the pin P in contact with the rod R, carrying it downward, and by means of the connection m and arms M 5 and N raises the sliding bolt O, thus permitting the lever K and its connection k' and the clutch h' to assume their normal position ready for a repetition of the operation.

What I claim is—

- 10 1. In combination, the frame or bed, the feed-rollers, the vertically-movable cutter-frame carrying the cutter, the cam for raising the cutter-frame normally out of action, the clutch for connecting the cam to a continuously-running part of the machine, the movable projection in the path of the section to be operated upon, operating connections whereby the movement of said projection will throw the cam into action, means for holding 15 the clutch-sections in engagement during the entire revolution of the cam, and means operated by the cam at the completion of its revolution for returning all the parts to normal position, substantially as described.
- 20 2. In a machine for planing taper-sections, the combination with a cutter and a cam for shifting the same, of the means for automatically starting said cam by the stock comprising the cam-shaft, the clutch, the pivoted lever K having an arm engaging one member 25 of the clutch, the lever I having a projection in the path of the stock, the link connecting

the lever I with the lever K and the sliding bolt for locking the lever K in one position, substantially as described. 35

3. In combination, the cutter, the cam for lifting the same, the cam-shaft, the clutch thereon, the lever K having an arm engaging one member of the clutch, the lever I having a projection arranged in the path of the stock 40 to be operated upon, the link connecting the lever I to the lever K, the bolt for locking the lever K in one position and the means for releasing the bolt, substantially as described.

4. In combination, the cutter, the cam for 45 lifting the same, the cam-shaft, the clutch thereon, the lever K having an arm engaging one member of the clutch, the lever I having a projection arranged in the path of the stock to be operated upon, the link connecting the 50 lever I to the lever K, the bolt for locking the lever K in one position, the pivoted arm engaging the bolt, the pin carried by said cam, the pivoted arm operated thereby, and the link connecting the arm with the arm engaging the bolt whereby the bolt is retracted, substantially as described. 55

In testimony whereof I affix my signature in presence of two witnesses.

LEANDER L. BARTLETT.
